UNITED STATES PATENT OFFICE.

FINIS E. ROACH, OF CHICAGO, ILLINOIS.

PYRO-ELECTRIC FURNACE.

No. 838,647.

Specification of Letters Patent.

Patented Dec. 18, 1906.

Application filed October 11, 1905. Serial No. 282,272.

To all whom it may concern:

Be it known that I, FINIS E. ROACH, a citizen of the United States, and a resident of Chicago, Cook county, Illinois, have invented 5 certain new and useful Improvements in Pyro-Electric Furnaces; and I do hereby declare that the following is a full, clear, and exact description of the same, reference being had to the accompanying drawings, and to the 10 letters of reference marked thereon, which form a part of this specification.

This invention relates to improvements in pyro-electric furnaces, and is shown more particularly embodied as a dental furnace 15 for the baking of porcelain and similar material, though obviously it may be used for many different purposes for heating or baking materials of any kind.

In furnaces heretofore devised for dental 20 use a considerable portion of heat has not been utilized, because it has been necessary to provide an opening in one side or one end or in the top of the furnace to permit the operation of the furnace to be carefully watched 25 by the operator, or if a closed furnace it has heretofore been necessary to frequently open or partly open the furnace to inspect the process of baking. In either case the material is exposed to a draft of air injurious to the material and permitting a large loss of heat 30 either through the view-aperture or while the furnace is open for purpose of inspection. Though attempts have been made in the past to apply mechanical devices for regulating 35 the heat, it has been, nevertheless, necessary for a trained operator to give the work careful attention to prevent injuring material treated, for the reason that large masses of material treated require longer period of time 40 and much more heat than smaller masses, and it has heretofore been very difficult, if not impossible, to adjust a furnace quickly to the heat required for a given material or for varying quantities of the material.

The object of this invention is to afford an 45 electric furnace in which the material treated is at all times wholly inclosed in the furnace and subjected to a high temperature, gradually increasing to a predetermined maximum 50 during a predetermined time.

It is also an object of the invention to afford mechanism whereby the furnace can be set to afford as a maximum any desired degree of heat within the range of the furnace 55 and adapted when said degree of heat has

been attained to break the circuit, permitting cooling.

The invention has also for its object a construction in which material treated is positively supported at approximately the center of the furnace, at the point of maximum heat.

It is also an object of the invention to so construct the furnace as to enable the heat to be applied instantaneously and uniformly to 65 all parts of the article heated, or the bake, during the entire period of heating and in which at a predetermined temperature the current will cease.

A further object of the invention is to afford 70 a construction in which the pyrometer can be quickly set to insure either a quick bake or a slower bake.

It is a further object of the invention to construct an automatically-operating furnace 75 in which the parts can be quickly assembled or as quickly separated and in which the heating element or muffle of the furnace can be lifted from the furnace.

The invention embraces many novel features; and it consists in the matters herein-after described, and more fully pointed out and defined in the appended claims.

In the drawings, Figure 1 is a side elevation of a furnace embodying my invention. 85 Fig. 2 is a vertical section thereof. Fig. 3 is a section taken on line 3 3 of Fig. 2. Fig. 4 is an enlarged fragmentary front elevation of a part of the pyrometer. Fig. 5 is a side elevation of the carrier for the thermostatic 90 slug. Fig. 6 is a section taken on line 6 6 of Fig. 4. Fig. 7 is a longitudinal section of the carrying-sleeve. Fig. 8 is a side elevation of the thermostatic slug. Fig. 9 is a view in elevation of the muffle. Fig. 10 is a similar elevation of the outer casing for the muffle. Fig. 11 is an enlarged fragmentary section of the muffle, showing the crimping of the resistance-wire. Fig. 12 is a view of the cover-base of the furnace with the pyrometer removed, showing the side rods broken. Fig. 13 is a longitudinal section of one of the separable binding-posts. Fig. 14 is a fragmentary side elevation of one of the contacts therefor. Fig. 15 is a section taken on line 105 15 15 of Fig. 13. Fig. 16 is a section taken on line 16 16 of Fig. 13. Fig. 17 is a side elevation, partly broken, showing the top of the furnace lifted from the furnace-base and supported on the insulating-base. Fig. 18 is a 110

top plan view of the furnace-base and the pan shown in Fig. 17. Fig. 19 is a similar view showing a flat plate used in lieu of the pan. Fig. 20 is a fragmentary side elevation 5 of the same. Fig. 21 is a fragmentary front elevation illustrating a preferred form of adjusting mechanism for the pyrometer. Fig. 22 is a section taken on line 22-22 of Fig. 21.

As shown in the drawings, A indicates an insulating-base, of slate or any suitable material. Secured thereon are upright parallel tubes a, one on each side of the center, as shown in Fig. 1 and in dotted lines in Fig. 3. These serve as standards to support the furnace, (indicated as a whole as B.) The base B' of said furnace is rigidly secured upon said tubes or standards a, which open therethrough, as shown in Figs. 18 and 19, and comprises an annular plate of metal or any suitable material secured thereon and a central upwardly-tapering tablet b, of refractory and non-conducting material, such as fire-clay, asbestos, or any suitable material. A central aperture is provided through the furnace-base and through said tablet, and rigidly secured therein is a cylindric sleeve C, which extends downwardly for a considerable distance below the bottom of the furnace and is longitudinally slotted in its front side and peripherally slotted, as shown in Fig. 4, to afford relatively short supporting-fingers c, adjacent each of which are marked numbers or characters, as shown "1" to "10," inclusive, which indicate the baking temperature 35 of different kinds of material to be treated or the duration of the treatment or the relative length of time during which the material is subjected to heat. Slidably secured in said graduated sleeve C is a tubular carrier having 40 on one side of the same a finger c', adapted to project through the slot in the sleeve and to be supported on the fingers c. The upper end of said carrier-tube c' is adapted to be projected above the base of the furnace and is provided with a tubular tip c'', which may be made of metal or of any refractory material and which, as shown, is provided near its upper end with an internal flange c'', above which the bore in the end of the tip is enlarged. The head of the fusible slug c''' is supported on the flange c'' in said tubular tip. Said furnace-base B' is provided with relatively large apertures therethrough on the rear side thereof, (indicated by b'') beneath 55 which and rigidly secured to the insulating-base A are metallic binding-posts D, each provided with a cylindric socket in its top and split longitudinally to afford resiliency. Pivoted on a post d' is a lever D'', the forward 60 end of which extends beneath the split sleeve or tube C or C' and is expanded to form a pan d''. The rear end of said lever is provided with a downturned flange d'', adapted to be engaged by the end of a leaf-spring d'', also secured on the insulating-base A. A con-

ductor d' leads from one of said binding-posts D to an ordinary binding-post D'. A conductor-wire d'' leads from the other binding-post D to the post d'', on which said lever is pivoted, and a conductor-wire d''' connects 70 the spring d'' with an ordinary binding-post D'', secured on the insulating-base A. Said binding-posts D' D'' are adapted for connection with the source of current-supply.

The furnace proper, or that part containing 75 the muffle, comprises a metallic shell B'', having secured therein at its bottom a plate B''', of metal or any suitable material, having a central aperture therethrough of a size to receive and fit around the central conical tablet b, as shown in Fig. 2, and which rests flat upon the furnace-base B'. The upper end or top of the shell B'' is closed by means of a metallic plate B'', rigidly secured thereto, and at the center of which is a projection B''', having an aperture therethrough, whereby the furnace can be lifted from the furnace-base.

Within the furnace and supported on the annular bottom plate B''' is an annular support or bottom E, of fire-clay, asbestos, or other suitable refractory and insulating material, and which projects inwardly partly over the tablet b, as shown in Fig. 2, and affords a support for the muffle. Said muffle, as shown, comprises a thin upwardly-tapering shell E', of insulating and refractory material—such as porcelain, fire-clay, or any suitable material—open at both ends and provided at its upper and lower edges with closely-arranged serrations, between which 100 and wound around and through the shell is the resistance-wire e. Preferably this wire is provided with a plurality of crimps, as shown in Fig. 11, at each bend as the same is passed through and around the muffle and 105 engages in the notches at each end thereof, thus increasing materially the quantity of wire and obviating any possible tendency to breakage due to expansion and contraction. As shown, said shell E', forming the muffle, 110 is split on one side for the entire length, and apertures are provided, one on each side of said slit near the bottom of the shell and through which the ends of the conductor-wires e are passed when the winding is completed, thus preventing short-circuiting where the wires enter and leave the muffle. Said muffle is supported upon a ledge of the insulating-support E, and over the same is secured a shell or cup E'', of porcelain or any 115 suitable material, out of contact therewith, but fitting closely thereto. Said shell or cup is provided with slots at the bottom of the same, through which the ends of the resistance-wire pass from the muffle, after 120 which said ends are carried upwardly over the cup, as shown in Fig. 3, and downwardly on the other side and inserted into a slot in the posts F, which, as shown, are two in number, positioned to project through the large 125 130

5 apertures in the base and register with the binding - posts D, before described. Said posts F are rigidly secured on the metallic bottom B³ of the furnace by means of an insulating-bushing f, which fits in suitable apertures in said annular bottom plate B³ and into which the posts F are screw-threaded. Engaged on each are binding-nuts f' and f'', between which the ends of the wires are 10 turned outwardly from the ends of the slot. The lower ends of said posts F are tapered at their extremity to fit into the sockets at the upper end of the split binding-posts.

15 The furnace-casing is filled with asbestos or any suitable non-conductive material, (indicated by B⁶,) which is closely packed about the shell E² and aids in holding the same in place and also prevents loss of heat by radiation.

20 Supported on standards g on the tablet b, which affords a closed bottom for the muffle, is a tray G. Said tray may be constructed of a pan having upturned edges and in which the article to be treated is placed, or it may 25 be constructed as a simple plate, (indicated by G' in Fig. 19.)

As shown, standards or legs H are provided on each side of the furnace, secured rigidly to the annular bottom plate B³ and registering 30 with the tubular standards a A³ and when the furnace is seated upon the furnace-base fit therein and hold the same in place. The lower ends h of said standards or legs H are 35 of smaller size and fit in suitable sockets h' in the insulating-base A, as shown in Fig. 17, thus supporting the furnace when removed from the base B³, or the same may be supported in the sockets h' in said furnace-base.

40 As shown in Fig. 21, the tube or split sleeve C' is constructed as before described, except that the peripheral slots and fingers are omitted and a lever K is pivoted on one of the standards a by means of a ring k, secured on the standard and having a flat face, 45 against which the end of said lever is engaged by a screw k' and washer k''. The free end of said lever is adapted for adjustment along the opposite standard A³, which is graduated to correspond with the grade or the baking 50 temperature of the material treated. Said tongue c' on the pyrometer or thermostat rests on said lever, so that movement of the lever produces corresponding adjustment of the same.

55 The operation is as follows: With the bake or article to be treated supported upon the tray G or G' approximately at the center of the muffle, where the temperature is highest, the muffle is placed upon the furnace-base B', with the legs or standards H fitting into the tubular standards a A³. The reduced and tapered ends f³ of the posts F engage in the sockets at the upper ends of the binding-posts D, as shown in Figs. 2 and 13, and are firmly clamped between the re-

5 silent ends of said posts. In this position the muffle is entirely closed and is held very securely upon the base B', with the tablet b partly within the insulating and spacing ring E. Before closing the furnace a slug of 70 metal—as, for instance, lead—which may be conveniently shaped, as shown in Fig. 8, to afford a peripheral flange at its upper end, is dropped into the upper end of the tubular carrier c³ and is supported therein with 75 its head in the countersunk end of said carrier. The carrier is now adjusted as to height by means of a lever before described or on the graduated fingers e to correspond with the character of material or the degree 80 of temperature to be attained in the furnace to perform the required operation. If a relatively low temperature is to be maintained for a short time, the slug is elevated, as shown in Fig. 2, to a point where it receives 85 practically the maximum heat of the furnace, and if a higher temperature is to be applied to the object treated the slug is adjusted downwardly to the point where it is in part protected from the heat thereof by 90 the surrounding walls. It is obvious that with the slug adjusted to a point below the floor of the furnace the time required to melt the slug will be much greater than when adjusted into the muffle and also that 95 a greater degree of heat is received at the middle of the furnace than at any part of the furnace intermediate the same and the floor. It follows that by means of the thermostat or pyrometer afforded by the construction 100 described the degree of heat and its duration can be determined by the position of the slug, which may be either a high or low fusing metal. The current flowing through the lever D² as one of the conductors is 105 instantly broken by the fall of said metal through the carrier and sleeve into the pan d', which strikes said end of the lever downwardly, releasing the spring, thus breaking 110 the circuit. The furnace, with the bake 115 therein, may then be allowed to cool, thus reducing the temperature slowly and avoiding any tendency toward cracking by sudden contraction, or the furnace may be lifted from the furnace-base and the reduced ends 120 h of the legs or standards inserted in the sockets h' at the rear of the insulating-base, as shown in Fig. 7, thus supporting the same in upright position, or, if preferred, the reduced ends of said legs may be inserted in 125 apertures h' in the furnace-base B', thus holding the same in upright position.

Obviously during the entire operation of the furnace the bake is positioned centrally within a muffle in which, being wound on both the inner and outer side, the maximum heat efficiency is attained. Furthermore, should a resistance-wire break all parts of the furnace are quickly accessible, and it is only necessary to twist the broken ends of the 130

wire together to restore the furnace to operative condition. This can usually be done by reaching into the muffle from the bottom, or, if preferred, the top plate B' and the packing may be removed and the muffle removed from the casing.

While I have described the furnace as cylindrical in form, it is obvious that other forms may be employed, and of course other forms of binding-posts, enabling the furnace to be quickly detached from the base B'. Obviously many details of construction may be varied, and I therefore do not purpose limiting this application for patent otherwise than necessitated by the prior art.

I claim as my invention—

1. In a furnace the combination with a base of an inclosed muffle fitted upon the same and wholly closed thereby, means for heating the muffle and heat-regulating means therefor, said furnace being opened by lifting the muffle from its base.

2. An electrical furnace comprising a base of refractory material and binding-posts, an inclosed muffle adapted to fit upon and to be entirely closed by said base and posts electrically connected with the muffle and adapted for sliding engagement with said binding-posts when the muffle is closed by the base.

3. An electrical furnace comprising a furnace-base, a muffle closed at the top and sides fitted thereon and completely closed thereby, electrical contacts adapted for sliding engagement one with the other, adapted to complete the circuit and thermostatic means acting to limit both the temperature of the furnace and the duration of the bake.

4. In a device of the class described, an inclosed muffle comprising an annular, split shell and resistance-wires around the inner and the outer side thereof, and having their ends extending therefrom at each side of the split.

5. In an electrical furnace, a muffle comprising a slit sleeve or shell having its edges notched at each end and a resistance-wire wound around the shell within and without the same, the turns engaging in the notches at the end of the shell, said wire being crimped to afford a plurality of bends at each turn.

6. In an electric furnace a muffle comprising an annular longitudinally-split shell notched at the ends, resistance-wires wound longitudinally around said shell, the turns lying in the notches and the ends thereof extending outwardly through suitable apertures at each side of the split, said wires being at the turns crimped to afford a plurality of bends at the upper and lower edge of the shell.

7. In a device of the class described a muffle comprising a tapered open-ended longitudinally-split shell of refractory and non-conducting material having closely-arranged

notches at each end thereof, a resistance-wire wound continuously around the inner and outer side of the shell the turns engaging in said notches and crimped at each turn to afford a plurality of bends, the ends of said wire extending through apertures in said shell on opposite sides of the slit and a casing of non-conducting and refractory material inclosing the top and sides of the muffle.

8. In a device of the class described a muffle comprising a tapered open-ended longitudinally-split shell of refractory and non-conducting material having closely-arranged notches at each end thereof, a resistance-wire wound continuously around the inner and outer side of the shell the turns engaging in said notches and crimped at each turn to afford a plurality of bends, the ends of said wire extending through apertures on said shell on opposite sides of the slit and a casing of non-conducting and refractory material inclosing the top and sides of the muffle and around and over which the ends of the resistance-wires lead.

9. In an electrical furnace a muffle comprising an annular shell of insulating material open at each end and split longitudinally in one side, a resistance-wire wound around through and through the same from one side of the slit around the shell to the other, and the ends thereof passing outwardly through suitable apertures on each side of the split, a cup of refractory material closing the top and sides of said muffle and bound thereto by the resistance-wires and acting to converge the heat inwardly and a bottom entirely closing the muffle and affording a support for the material treated.

10. An electric furnace comprising a muffle inclosed at the top and sides, a removable close-fitting bottom therefor, binding-posts rigidly connected with the muffle and with which the ends of the resistance-wire are connected, and complemental binding-posts on the furnace-base adapted to engage the same to afford a sliding connection.

11. An electric furnace comprising a muffle inclosed at the top and sides, a removable close-fitting bottom therefor, binding-posts rigidly connected with the muffle and with which the ends of the resistance-wire are connected, complemental binding-posts on the furnace-base adapted to engage the same to afford a sliding connection and thermostatically-operated means acting to break the circuit at a predetermined temperature.

12. In a furnace the combination with a furnace-base of a central refractory tablet secured thereon, a muffle closed at its sides and at one end and adapted to be closed at the bottom by said tablet, non-conducting packing surrounding the muffle and an adjustable thermostat adapted to be set to operate at a predetermined temperature and acting to turn off the heat automatically.

13. An electrical furnace comprising an electrically-heated muffle wholly closed, a removable bottom therefor, a support on the bottom, a pan secured on the bottom and actuating to support the material treated approximately at the center of the muffle, packing material inclosing said muffle, a thermostat or pyrometer, communicating with the interior of the muffle and adapted for adjustment to a wide range of temperatures and means connected in the electrical circuit and operated by the thermostat to break the circuit at temperature for which the thermostat is set.
14. In a device of the class described the combination with a furnace-base of a refractory tablet supported thereon at its middle, an electrically-heated muffle closed at its top and sides and adapted to fit over the insulating refractory tablet on the base, thereby wholly closing the muffle, a support on said tablet positioned approximately at the center of the muffle for the material treated, a regulable and graduated thermostat engaged on said base and adapted to break the circuit at a predetermined temperature and standards or legs on the furnace adapted to afford a support therefor clear from the furnace-base.
15. In a device of the class described the combination with a muffler of means inclosing the same, a resistance-coil in said muffler, a support in the muffler and a vertically-adjustable carrier below said support.
16. In a device of the class described the combination with a muffler of means inclosing the same, a resistance-coil wound about said muffler, electric conductors connected therewith, vertically-adjustable thermostatic means connected with said muffler and means operated thereby at a predetermined temperature adapted to break the circuit.
17. In a device of the class described the combination with a furnace-base of an annular muffler supported thereon, means closing each end of said muffler, means for heating said muffler, a sleeve rigidly engaged in said base and opening upwardly to said muffler and vertically-adjustable means in said sleeve adapted to cut off heat at a predetermined temperature.
18. In a device of the class described the combination with a furnace-base of a muffler carried thereon, means closing the ends of said muffler, a resistance-coil wound about said muffler, conductors connected therewith, a lever normally connected with said conductors and forming part of the circuit, a vertically-adjustable carrier supported in said base and means therein adapted at a predetermined temperature to operate said lever and break the circuit.
19. In a device of the class described the combination with a furnace-base of an inclosed muffler thereon, a resistance-coil on said muffler, posts connected therewith and projecting through said base, an insulating-base and split binding-posts thereon adapted to receive said posts.
20. In a device of the class described the combination with a furnace-base of an inclosed muffler supported thereon, a resistance-coil on said muffler, posts in said base through which the ends of said coil extend, an insulating-base, split binding-posts thereon adapted to receive the posts in the furnace-base and supporting means connected with said furnace-base and the insulating-base.
21. In a device of the class described the combination with a furnace-base of a muffler supported thereon, non-conducting material inclosing said muffler, a resistance-coil on said muffler, an insulating-base rigidly engaged to the furnace-base, binding-posts thereon adapted for engagement with the resistance-coil, a vertically-adjustable carrier in said furnace-base and projecting into the muffler, a lever carried on the insulating-base and normally forming part of the circuit and fusible means on said carrier adapted at a predetermined temperature to operate said lever to break the circuit.
22. In a device of the class described the combination with an insulating-base of tubular standards thereon, a furnace-base engaged on said standards and provided with apertures opening thereinto, a tapering tablet on said base, an inclosed muffler supported thereon a resistance-coil on said muffler, an annular bottom plate surrounding said tablet, posts thereon extending downwardly through the base and adapted to receive the ends of said coil therein, split binding-posts on said insulating-base adapted to engage said posts, legs on said annular bottom plate adapted to engage in said standards, an electric circuit connected with said coil and means for breaking the same at a predetermined temperature.
23. In a device of the class described the combination with an insulating-base of a furnace-base supported above the same, an inclosed muffler on said furnace-base, a resistance-coil thereon, conductors connected with said coil, a sleeve extending upwardly through the furnace-base, a hollow carrier therein adapted to contain a fusible slug, means for adjusting said carrier with respect to said muffler and a lever carried on said insulating-base and forming part of the circuit and adapted when said slug is fused to break the circuit.
24. In a device of the class described the combination with a furnace-base of a tablet therein, a muffler supported on said tablet, a resistance-coil on said muffler, means for connecting said coil in an electric circuit, a slotted sleeve engaged in said base and opening to said muffler, a hollow carrier adjust-

ably engaged in said sleeve, a finger thereon projecting through the slot in said sleeve, means adapted to engage said finger and hold the carrier in adjusted position and
5 means beneath the sleeve adapted to break the circuit at a predetermined temperature.

In testimony whereof I have hereunto sub-

scribed my name in the presence of two sub-
scribing witnesses.

FINIS E. ROACH.
